ATTORNEYS.

the nut immediately surrounding said threaded opening and said nut in its clinched condition on said plate having a portion of said recess remaining in said top in surrounding relation to the end of said threaded opening.

2. A clinch nut adapted to be connected to a plate, said nut having lateral shoulder means adapted to engage one side of the plate, and having a substantially square projection adapted to extend into a similar opening in the plate, substantially the entire top of said projection conforming to a portion of the surface of a cylinder so as to provide said top with an arcuately concave recess, said clinch nut having a threaded opening substantially centrally thereof and extending thereinto from the bottom of the arcuately concave recess of said top, said projection also having relatively elevated substantially parallel top edge portions on opposite sides of said recess, the height of said projection between said shoulder means and the top of said relatively ele-

vated substantially parallel edge portions of the projection being greater than the thickness of the plate and the depth of said arcuately concave recess being such that said top edge portions will extend beyond the other side of the plate and are adapted to be deflected laterally into overhanging relation to said other side of the plate substantially without distortion of any portion of the nut immediately surrounding said threaded opening.

FREDERICK G. RICHARDSON.
